US00D930578S

(12) **United States Design Patent** (10) **Patent No.:** **US D930,578 S**
(45) **Date of Patent:** **** Sep. 14, 2021**

(54) **POWER SUPPLY**

(71) Applicant: **Aukey Technology Co., Ltd**, Shenzhen (CN)

(72) Inventors: **Huahui Zheng**, Shenzhen (CN); **Bo Du**, Shenzhen (CN); **Haizhuan Lu**, Shenzhen (CN)

(73) Assignee: **Aukey Technology Co., Ltd**, Shenzhen (CN)

(**) Term: **15 Years**

(21) Appl. No.: **29/722,989**

(22) Filed: **Feb. 4, 2020**

(51) LOC (13) Cl. **13-02**

(52) U.S. Cl.

USPC **D13/107**; D13/110

(58) **Field of Classification Search**

USPC D13/103, 106, 107, 108, 109, 110, 112, D13/116, 118, 119, 152, 184, 199; D14/432, 433, 434

CPC H02J 7/0027; H05K 5/00; F02N 11/2

(57) **CLAIM**

The ornamental design for a power supply, as shown and described.

DESCRIPTION

FIG. 1 is a front, left, top perspective view of a power supply showing our new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged top, front perspective view of the detail identified in FIG. 1.

The broken lines depict portions of the power supply that form no part of the claimed design.

1 Claim, 9 Drawing Sheets
